UNITED STATES PATENT OFFICE.

ERASmus C. QUIMBY AND PAUL W. QUIMBY, OF LOS ANGELES, CALIFORNIA.

DESIGN FOR A BOX.

54,451.

Specification for Design.

Patented Feb. 10, 1920.

Application filed August 19, 1918. Serial No. 250,611. Term of patent 14 years.

To all whom it may concern:

Be it known that we, ERASmus C. QUIMBY and PAUL W. QUIMBY, citizens of the United States, residing at Los Angeles, county of Los Angeles, State of California, have invented a new, original, and ornamental Design for Boxes, of which the following is a specification, reference being had to the accompanying drawings, forming a part thereof.

The figure is a perspective view of the box.

We claim:

The ornamental design for a box as shown.

ERASmus C. QUIMBY.
PAUL W. QUIMBY.
